United States Patent Office

Des. 189,612
Patented Jan. 17, 1961

189,612

BUILDING

James E. Wheeler, 2256 Kent Blvd, NE,
Grand Rapids, Mich.

Filed Mar. 20, 1959, Ser. No. 55,080

Term of patent 14 years

(Cl. D13—1)

Fig. 1.

Fig. 2.

Fig. 3.

Fig. 4.

Fig. 1 is a top perspective view of the building embodying my new design;

Fig. 2 is a top plan view;

Fig. 3 is an enlarged side elevational view; and

Fig. 4 is an enlarged rear elevational view as seen from the rear of Fig. 3.

The right side of the building of Fig. 1, which is not shown, is substantially identical to the left side of the building as shown in the drawing.

I claim:

The ornamental design for a building, substantially as shown and described.
